UNITED STATES PATENT OFFICE.

JOHN H. TEUTEBERG, OF MILAN, MISSOURI.

SAFETY-STIRRUP.

1,158,746.

Specification of Letters Patent.

Patented Nov. 2, 1915.

Application filed September 16, 1912. Serial No. 720,627.

To all whom it may concern:

Be it known that I, JOHN H. TEUTEBERG, a citizen of the United States, residing at Milan, in the county of Sullivan and State 5 of Missouri, have invented new and useful Improvements in Safety-Stirrups, of which the following is a specification.

My invention relates to the class of stirrups and more particularly to a safety stirrup, the primary object of which is to provide a novel and peculiar device of this character which can be readily and quickly detached from its support by the pressing of the foot of the rider against a releasing lever should a runaway occur or should he be accidentally thrown from his mount, whereby such accidents as often result from a dismounted rider's inability to extract his foot from the stirrup are obviated.

Another object of my invention is to provide a releasing device in connection with the stirrup whereby the latter is automatically released from its support should a rider be thrown from his mount and fall to the ground, such automatic action occurring through the medium of a spring controlled lever depending from the support in the path of the rider's foot.

30 A further object of my invention is to provide a device of the character described which comprises a few simple parts, is simple in construction, efficient in operation, and one which can be manufactured and 35 placed upon the market at a minimum cost.

With the foregoing and other objects in view, my invention relates to such details of construction and in the arrangement and combination of the several parts as will be 40 hereinafter more fully described and set forth in the appended claims.

In describing my invention in detail reference will be had to the accompanying drawings wherein like characters denote 45 like or corresponding parts throughout the several views and in which;

Figure 1 is a front elevation of a safety stirrup. Fig. 2 is a side elevation. Fig. 3 is a section on the line $a-a$ Fig. 1, and Fig. 50 4 is a similar view showing the stirrup released and ready to fall from its support.

Referring to the drawings the numeral 1 designates a stirrup supporting frame from which depends at each side thereof an arm 55 2 of substantially the same contour as the

stirrup 3 and which terminates in ears 4, between which the stirrup sides fit so as to form guides and braces against lateral movement thereof.

My stirrup releasing mechanism while 60 automatic and certain in operation is composed of but a few simple parts. A releasing lever 5 of substantially the same curvature as the arms 2, is provided and supported by means of a hook shaped head 6 which member is pivotally suspended within an opening 7 of the frame 1 and through the medium of the pin 8 extending across the said opening and secured within the frame sides. This lever 5 is normally held away 65 from the stirrup 3 as illustrated in Fig. 2 of the drawings by the spring 9 coiled about the pin 8 within a groove or cutout portion 10 provided upon the under side of the head 6, one end of the spring adapted to press 70 against the inner face of the lever 5 while its other end is adapted to press upon a cross-bar 11 of the frame.

The peculiar shape of the head 6 is such as 75 to permit one end thereof to normally hold the stirrup suspended from within the frame, by reason of its fitting within the slot 12 provided upon the top of the stirrup.

It is apparent from the description, taken 80 in connection with the accompanying drawings, that the operation of my device is automatic and simple in the extreme. Its operation being as follows: Should a rider be 85 dismounted for any reason whatsoever, the foot remaining within the stirrup would necessarily come in contact with the releasing lever 5 in which event the head 6 is forced 90 against the cross bar 11 thereby releasing its hold upon the stirrup and permitting the same to drop from its suspended position 95 within the frame.

By constructing the releasing lever as hereinbefore described the same will in no way interfere with the rider's foot under ordinary circumstances but should the rider 100 lose his mount and his foot become hooked within the stirrup as often occurs, such action would automatically release the stirrup and permit the removal of the foot.

Attention is called to the fact that the releasing operation is absolutely certain, that the frame may be secured to the stirrup strap in any suitable manner, (preferably as illustrated), and that the frame may be constructed entirely of one piece of metal, or 105 110 113

of a number of pieces whichever is found cheapest upon practical application of the invention.

It is thought from the foregoing that the 5 advantages and novel features of my device will be fully appreciated.

I desire it to be understood that I may make slight changes in the construction and in the arrangement and combination of the 10 several parts, provided such changes fall within scope of the subjoined claims.

Having thus fully described my invention what I claim as new and desire to secure by Letters Patent is:—

15 1. In a device of the character described, the combination of a stirrup having a slot at the upper end thereof, a frame having arms of substantially the same contour as the stirrup and terminating in ears to prevent lateral movement of the said stirrup, a head pivoted within an opening within said frame by means of a pin, a releasing lever depending from one end of said head, and a spring carried by said pin and adapt-

ed to engage said head for normally holding 25 the head within the slot of the stirrup, the depressing of said lever forcing the head out of said slot for releasing the said stirrup from its supporting frame, substantially as and for the purpose set forth.

2. A safety stirrup including a supporting frame, an arcuate head pivotally mounted in said frame, said head being provided with a cut-out portion on the inner face thereof and arranged approximately midway the 35 ends thereof, a stirrup detachably carried by the one end of said head, a lever rigidly carried by the opposite end downwardly therefrom adapted to release said stirrup from said head, when pressure is exerted 40 thereon, and a spring arranged in the cut-out portion of said head and having connection with said frame for normally holding said lever beyond said stirrup.

JOHN H. TEUTEBERG.
